CLAIM

The ornamental design for a hair brush as shown.

DESCRIPTION

FIG. 1 is a front perspective view of a hair brush showing my new design.

FIG. 2 is a rear perspective view thereof.

FIG. 3 is a front view thereof.

FIG. 4 is a rear view thereof.

FIG. 5 is a right side view thereof. The left side view is a mirror image of the right side view.

FIG. 6 is a top view thereof.

FIG. 7 is a bottom view thereof.

FIG. 8 is a front perspective view of another embodiment of a hair brush showing my new design.

FIG. 9 is a rear perspective view thereof.

FIG. 10 is a front view thereof.

FIG. 11 is a rear view thereof.

FIG. 12 is a right side view thereof. The left side view is a mirror image of the right side view.

FIG. 13 is a top view thereof.

FIG. 14 is a bottom view thereof.

FIG. 15 is a front perspective view of another embodiment of a Hair Brush showing my new design.

FIG. 16 is a rear perspective view thereof.

FIG. 17 is a front view thereof.

FIG. 18 is a rear view thereof.

FIG. 19 is a right side view thereof. The left side view is a mirror image of the right side view.

FIG. 20 is a top view thereof; and,

FIG. 21 is a bottom view thereof.
